ELECTRIC SWITCHING DEVICE

Ferman C. Doughman and Eric C. Wahlberg,
Stamford, Conn., assignors to Electrolux Corporation, New York, N. Y., a corporation of Delaware

Application June 4, 1942, Serial No. 445,696

11 Claims. (Cl. 203—97)

Our invention relates to an improved electric switching device, and more particularly to a switch having a plurality of positions and including means for automatically retaining the switch in at least one of such positions for a comparatively short though appreciable length of time.

More specifically, our invention relates to a snap-action switch having two terminal positions and an intermediate position. A switch of this nature includes means for rapidly throwing the switch from one terminal position to the other when a switch handle is actuated. In accordance with our invention means are provided for automatically interrupting in an intermediate position the throw of the switch which has been initiated by actuating the handle. The switch is held in this intermediate position for a short interval and is then automatically released to continue to travel to the other terminal position without further manipulation by the operator.

While a switch having these general characteristics may find wide application in the electrical art, the particular switch herein shown and described is especially suited for controlling in a simple manner the operation of the system including a plurality of electric motors as shown and described in co-pending application Serial No. 428,018 filed January 24, 1942, by Eric C. Wahlberg.

Further objects and advantages of our invention will be apparent from the following description considered in connection with the accompanying drawings, which form a part of this specification and of which:

Fig. 1 is an elevational view of a switching device in accordance with our invention;

Fig. 2 is a cross-sectional view on an enlarged scale of the device shown in Fig. 1;

Fig. 3 is a cross-sectional view taken on the line 3—3 of Fig. 2;

Fig. 4 is a cross-sectional perspective view on a still larger scale of a portion of the device illustrated in the preceding figures;

Fig. 5 is a view of a portion of the apparatus illustrated in Fig. 2, but showing certain of the parts in different positions;

Fig. 6 is a rear view of a portion of a switching device showing a modification;

Fig. 7 is a cross-sectional view taken on the line 7—7 of Fig. 6;

Fig. 8 is a view similar to Fig. 7, but showing certain parts in different positions; and

Fig. 9 is a wiring diagram illustrating the man-

ner of connecting a switch in accordance with our invention in an electrical system.

Referring more particularly to Figs. 1 to 5, reference character 10 designates generally a snap-action switch which is secured by means of a bracket 12 to the casing of a time-delay solenoid device 14.

Switch 10 includes a frame or chassis 16 on which is mounted a composite block of insulating material 18 formed with an arcuate surface 20. Mounted in grooves in the face of the block is a plurality of electric contact members 22, 24, 26, 28, 30, 32, 34 and 36 provided with binding screws or other suitable terminals for the connection thereto of conductors. All of these contacts are provided with arcuate track surfaces which conform to the curvature of the surface 20 of the block 18, but are so arranged with respect to the surface that they will be contacted by suitable metal rollers, as will appear herein-after.

Contacts 22 and 24, constituting one set, are disposed close to each other in the same groove so as to be bridged by one roller. These contacts are of equal length and the arcuate tracks thereof extend from one end of the arcuate surface 20 on the insulating block to a short distance beyond the center of the surface 20.

Contacts 26 and 28 are located in alignment with each other, but separated by a portion of the insulating block 18. These two contacts are placed closely adjacent to the contact 30 and in the same groove. This latter contact is of the same length as the contacts 22 or 24, whereas the contact 26 ends short of the center of the block, while the contact 28 is located at the center and extends a short distance on either side thereof. The relative location of the contacts 26, 28 and 30, which constitute another set, is such that a roller may bridge contacts 26 and 30, or contacts 28 and 30, depending upon the position of the roller.

Contacts 32, 34 and 36, constituting a third set, are arranged in the same manner as contacts 26, 28 and 30.

Pivotedly mounted on the switch frame 16 at 38 is a switch-actuating handle 40. The inner end of this handle is provided with a pin 42 which extends through a slot 44 formed in a switch arm 46. One end of a coil spring 48 bears against the pin 42, while the opposite end of the spring is anchored to the switch arm 46. The opposite end of the arm is formed as a blade 50 of insulating material, as is best seen in Fig. 4. This blade carries three metal rollers 52 which

are rotatably mounted in the edge of the blade portion, each roller being so located as to run in one of the grooves and to bridge the set of contacts therein.

Pivotedly mounted at 54 on the frame of the switch is a member 56. This member carries one or more projections 58 which extend through suitable openings formed in the insulating block 18 between the contacts carried thereby. These openings are located at the center of the arcuate surface 20, so that the projections 58 are disposed in the path of travel of the blade 50 and will stop the latter in an intermediate position with the rollers bridging contacts 22 and 24, 28 and 30, and 34 and 36, respectively.

Member 56 is formed with an arm 60 which extends at substantially right angles to the rest of the member. The free end of this arm is provided with a slot 62 through which extends a spindle 64 of the time-delay device 14. This spindle is threaded and provided with lock nuts 66 above and below the arm 60, the nuts being spaced sufficiently so as to permit pivoting of the arm with respect to the spindle when the latter is moved up and down. The upper end of the spindle is secured to the central portion of a diaphragm 68, the outer edge of which is clamped between a body member 70 and a lower head 72. The lower surface of the body member 70 is recessed so as to form, together with the diaphragm, a diaphragm chamber 73.

The upper surface of the body member 70 is likewise recessed and a diaphragm 74 is clamped between the upper edge of the body and a ring 76 bolted thereto, so as to form an expansion chamber 78. A coil spring 80 is disposed between the body member and the diaphragm 74. The body member 70 is formed with a passageway 82 connecting diaphragm chamber 73 with expansion chamber 78. The rate of flow of fluid through this passageway may be controlled by means of a needle valve 84 adjustable from the exterior of the body 70 by means of a knurled knob 86.

Chambers 73 and 78 are also connected by means of a passageway 88 which is normally closed by a check valve 90 which is held against an annular seat 92 by means of a spring 94. A member 96 is disposed between the valve disc 90 and the lower surface of the body member 70. One end of the member 96 engages the edge of the disc, while an intermediate portion bears against the surface of member 70. The opposite end of the member 96 extends downwardly, as is shown at 98, so as to be contacted by the diaphragm 68 after the latter has been raised a certain amount. When the diaphragm strikes the projection 98 it pivots the member 96 about its point of contact with the member 70 as a fulcrum, thus moving the other end of the member 96 downwardly so as to tilt the valve disc 90 away from its seat 92.

The body member 70 and associated parts are supported by legs 100 above a casing 102, to which the bracket 12 is connected. An electromagnet coil 104 is mounted within the casing. An armature member 106 is slidably positioned on the spindle 64 and normally rests against a lower stop 108. A coil spring 110 is disposed between the upper end of the armature member and a nut 112 which has threaded engagement with the upper end of the spindle. An annular member 114 is secured within a circular opening formed in the top of casing 102 and is provided with a ring of resilient material 116 located at

the inner end of a conical recess formed in the lower face of member 114. The upper end of armature 106 is conical and is adapted to seat against the ring 116 in the recess.

In Fig. 9 there is shown a wiring diagram of an electrical system embodying the above-described switching mechanism. The system includes a plurality of direct-current motors including field poles 120 and 122 and armature coils 124. Each armature coil is connected to the segments of a commutator 126 by means of the usual taps 128. In addition, each armature includes three slip rings 130, 132 and 134 which are connected to the armature winding at spaced points by means of taps 136, 138 and 140. Brushes 142, 144 and 146 are associated with the slip rings, corresponding brushes of the different motors being connected together by means of conductors 148, 150 and 152.

10 The field coils of the separate motors are connected in series by means of conductors 154 and 156, the field coil of the right-hand motor being connected to ground by means of conductor 158, while the field coil of the left-hand motor is connected to the contact 22 of the switch 10 by means of a conductor 160. The contact 24 of the switch is connected to one side of a suitable supply of excitation current by means of a conductor 162, the other side of the supply circuit being grounded. Each motor is provided with a pair of commutator brushes 164 and 165 connected in parallel to conductors 166 and 170, respectively. Conductor 168 is connected to contact 32 of the switch, while conductor 170 is connected to contact 26. Contact 36 is connected by means of a conductor 172 to one side of a suitable source of armature current, the other side of the circuit being grounded, and contact 30 is connected to ground by means of a conductor 174.

20 Conductor 150 is connected to contact 28, while conductor 152 is connected to contact 34. Conductors 176 and 178 connect conductors 150 and 152, and hence contacts 28 and 34, respectively, with the solenoid coil 104 of the time-delay device 14.

30

40 The above-described switching mechanism, when connected in the circuit illustrated in Fig. 9, operates as follows. It is assumed that the switch is in the position illustrated in Figs. 1 and 2, which is the position designated I in Fig. 9. In this position the rollers 52 are beyond all of the contacts and consequently all of the circuits through the switch are open and the motors are stationary. When it is desired to start the motors, the switch handle 40 is pivoted in a clockwise direction, as viewed in Figs. 1 and 2. This straightens out the toggle formed by the switch handle and the member 46, the spring 48 being compressed. After the switch handle has been pivoted a certain distance, the spring 48 causes the switch arm 46 to be suddenly thrown toward its other extreme position, as is characteristic of snap-action switches. However, the throw of the switch is interrupted at a midpoint 65 by the blade 50 striking the projections 58 and the switch is stopped in the midpoint designated by II in Fig. 9. However, the spring 48 still tends to throw the switch to the extreme position designated by III.

50 In the position II one of the rollers bridges the contacts 22 and 24, thus closing the field circuit and supplying excitation current to the coils of the poles 120 and 122. Another of the rollers bridges the contacts 28 and 30, while the third roller bridges the contacts 34 and 36. Arma-

60

70

75

ture current is thus supplied from the conductors 172 and 174 to the conductors 150 and 152 and hence through the brushes 144 and 146, the slip rings 132 and 130, and the taps 138 and 136 to the armature windings 124 of each motor. As explained in detail in the above-mentioned application Serial No. 428,018, there is thus established relatively fixed magnetic poles in the armatures. Inasmuch as the field coils are excited, each armature is turned through the necessary angle to bring it into a fixed angular position with respect to the field and consequently the several armatures are brought into fixed angular position with respect to each other.

At the same time that current is supplied to the conductors 150 and 152, it is also supplied through the conductors 176 and 178 to the solenoid coil 104. Energization of this coil causes the armature 106 to be immediately moved upwardly until it contacts the resilient ring 116. The air contained within the diaphragm chamber 68 resists upward movement of the diaphragm, and consequently the spring 110 is compressed. This spring tends to move the diaphragm upwardly and the air in the diaphragm chamber 73 is forced to flow through the passage 82 and past the needle valve 84 to within the expansion chamber 78. As this occurs the diaphragm moves slowly upwardly until it strikes the projection 98 on the member 96. Further movement of the diaphragm causes the member 96 to pivot so as to tilt the valve 90 away from the annular seat 92, thus establishing a substantially unobstructed path for flow of air through the passage 88 to the expansion chamber, which permits the diaphragm to be moved suddenly upwardly. This movement of the diaphragm and the spindle 64 connected thereto, causes the member 56 to pivot in a clockwise direction, thus withdrawing the projections 58 from engagement with the blade 50 of the switch, whereupon the spring 48 causes the switch member 46 and blade 50 to resume its travel to the position III. The length of time during which the switch is held in the intermediate position II depends on the adjustment of the needle valve 84, and this valve is adjusted to hold the switch in the intermediate position long enough for the armatures to be turned into angular alignment.

In the position III the contacts 22 and 24 are still bridged by one of the rollers and consequently excitation current is still supplied to the field windings. However, in this position contacts 26 and 30 and contacts 32 and 36 are bridged, thus supplying armature current through the conductors 168 and 170 to the brushes 164 and 165 of the several motors. This causes the motors to operate in the normal manner. Due to the three-phase connection through the conductors 148, 150 and 152 between the several motors, they are caused to operate in synchronization.

The switch is left in the position III as long as operation of the motors is desired. With the switch in this position, the circuit of the solenoid coil 104 is open and consequently armature 106 drops against the stop 108 on the spindle 64 and the weight of the armature tends to return the diaphragm 68 to the position shown in Fig. 2. This reduces the pressure of the diaphragm chamber 73 and the spring 94 permits the valve 90 to open under the influence of the higher pressure existing in the expansion chamber 78. In this way, the diaphragm is returned to its lower position much more rapidly than would be

the case if it were necessary for the air to flow past the needle valve 84. As the diaphragm returns to its lower position, the member 56 is pivoted in a counterclockwise direction so as to bring the projections 58 into the path of travel of the blade 50.

When it is desired to stop the motors, the switch handle 40 is pivoted in a counterclockwise direction, thereby causing the switch arm 46 to travel from the position III toward the position I. The blade strikes the underside of the projections 58 and is held in this intermediate position in the same manner as above described. The contacts 22 and 24 are still bridged and consequently excitation in the field coils is maintained. Contacts 28 and 30 and contacts 34 and 36 are now bridged, and consequently direct current is supplied to the conductors 150 and 152. This establishes relatively fixed magnetic poles in the armatures, as previously described, with the result that all of the armatures are brought to rest in angular alignment, as is described more in detail in the above-mentioned application Serial No. 428,018.

In this position of the switch the solenoid coil 104 is energized and the action of the time-delay device 14 is the same as above described. Consequently, after a short interval of time the projections 58 are withdrawn from engagement with the blade 50, whereupon the switch arm, under the influence of spring 48, continues to the position I, where all circuits through the switch are open and the motors are at rest.

The positions II and IV, as shown in Fig. 9, are electrically the same, but mechanically they differ in that the blade 50 is on opposite sides of the projections 58. Thus, when the switch is thrown from the position illustrated in Fig. 2 (position I of Fig. 9) it strikes the upper side of the projections. Consequently, the force of spring 48, which tends to move the switch downwardly, also tends to pivot the member 56 in a clockwise direction, and hence the force of this spring aids the spring 110 in withdrawing the projections 58 from engagement with the blade.

However, when the switch is thrown from the lower position in Fig. 2 (position III of Fig. 9) the blade 50 strikes the lower side of projections 58 and consequently the spring 48 tends to turn the member 56 in a counterclockwise direction. Therefore, it resists the tendency of spring 110 to withdraw the projections 58 from engagement with the blade. Consequently, the switch will be held in the position IV for a greater length of time than in the position II. Ordinarily this is not objectionable, inasmuch as the switch occupies the position IV when the motors are being stopped and a slight additional delay is not harmful. On the contrary it may even be advantageous inasmuch as under some conditions a longer period is required to stop the motors than is required to initially align the armatures.

However, if the difference in the length of time during which the switch occupies the positions II and IV, respectively, is found to be objectionable, the switch illustrated in Figs. 6 through 8 may be employed. The switch here shown is the same as that previously described, with the exception of the pivoted member 56 and the projections 58. As will be seen from Figs. 6 through 8, a member 180 is pivoted at 54 and is provided with an arm 60 which extends between the lock nuts 66 on the spindle 64 of the time-delay device 14. Member 180 carries one or more projections 182 which are normally disposed in the

path of travel of the blade 50. These projections do not extend at exactly 90° from the member 180, as was the case in the previously described embodiment, but the upper angle between the member 180 and the projections, as viewed in Fig. 7, is slightly greater than 90°. A member 184 is pivotally secured to the switch frame at 185 and extends above the lower end of member 180. As more particularly shown in Fig. 6, members 180 and 184 do not overlap laterally, but each is provided with cutaway portions for accommodating the forked end of the other. Member 184 is provided near its upper end with brackets 186 which embrace pins 188 extending laterally from the lower end of member 180. Member 184 carries projections 190 disposed beside the projections 182 and forming a lower angle, as viewed in Fig. 7, of slightly more than 90°.

With the switch in the position shown in Fig. 7, both the projections 182 and 190 are disposed in the path of travel of the blade 50. As the blade moves downwardly from the position shown it strikes the projections 190 carried by the pivoted member 184, inasmuch as the inner ends of projections 190 are slightly above the inner ends of projections 182. The force of the spring 48 tends to pivot the member 184 in a clockwise direction about the point 185 and consequently tends to hold the projections 190 in engagement with the blade 50.

On the other hand, when the switch is thrown from the lower position the blade strikes the projections 182 carried by the member 180 and the force of the spring 48 tends to pivot this member in a counterclockwise direction about the point 54 and consequently tends to retain the projections 182 in engagement with the blade. In other words, the force of the spring 48 in both cases acts the same on the projections which are contacted by the blade and therefore the switch will be retained in the intermediate position for the same length of time, regardless of whether the switch is being thrown from the position I toward the position III or vice versa.

When the switch is in the intermediate position, the solenoid of the time-delay device 14 is energized, as previously described, and after a short interval the spindle 64 is raised. This causes the member 180 to be pivoted in a clockwise direction which in turn causes the member 184 to be pivoted in a counterclockwise direction by virtue of the pins 188 engaged by the brackets 186. Consequently, both projections 182 and 190 are withdrawn from the path of travel of the switch blade.

While we have shown and described two more or less specific embodiments of our invention, it is to be understood that this has been done for purposes of illustration only and that the scope of our invention is not to be limited thereby, but is to be determined by the appended claims. Moreover, while we have shown our improved switching mechanism connected in a particular circuit, this has been done merely to illustrate one advantageous use of the device. Obviously, a switch in accordance with the invention may be employed in other circuits, either with the contacts as shown or arranged in other manners according to the requirements of the particular circuits.

What we claim is:

1. In a switch having two extreme positions and an intermediate position, means capable of

being conditioned to throw said switch from either extreme position to the other extreme position, a member movable to condition said means, and means for interrupting the throw of the switch from either extreme position to the other and for retaining the switch for an appreciable period in the intermediate position.

2. In a switch, a movable switch arm having two extreme positions and an intermediate position, means capable of being conditioned to throw said arm from either extreme position to the other, a member movable to condition said means, structure normally positioned in the path of travel of said arm for interrupting the throw

from either extreme position in said intermediate position, and means for clearing said structure from engagement with said arm after the latter has been retained in said intermediate position for an appreciable length of time.

3. In a switch, a movable switch arm having two extreme positions and an intermediate position, means capable of being conditioned to throw said arm from either extreme position to the other, a member movable to condition said means, structure normally positioned in the path of travel of said arm for interrupting the throw

from either extreme position in said intermediate position, an electric circuit connected so as to be closed by said arm in said intermediate position, means actuated by the closing of said circuit tending to release said structure from engagement with said arm, and means for delaying the release for an appreciable length of time.

4. In a switch, a movable switch arm having two extreme positions and an intermediate position, means capable of being conditioned to throw said arm from either extreme position to the other, a member movable to condition said means, structure normally positioned in the path of travel of

said arm for interrupting the throw from either extreme position in said intermediate position, an electric circuit connected so as to be closed by said arm in said intermediate position, an electromagnetic device connected in said circuit and actuated by the closing of the circuit so as to tend to release said structure from engagement with said arm, and dashpot means for delaying the release for an appreciable interval.

5. In an electric switching device, a snap-action switch including switch structure movable over a track between two terminal positions, means for moving said structure, a member normally positioned in the path of travel of said structure for arresting movement thereof from either terminal

position in an intermediate position, contacts bridged by said structure when in said intermediate position, an electro-magnet connected to be energized by the bridging of said contacts, said electro-magnet including an armature, means connecting said armature to said member so as to tend to withdraw said member from said path of travel when the electro-magnet is energized, and means for delaying the withdrawal of said member.

6. In an electric switching device, a snap-action switch including an arcuate track, an arm carrying a contact roller movable over said track between two terminal positions, means for moving said arm, a pivotally mounted member, a projection carried by said member and normally positioned in the path of travel of said arm for arresting movement thereof in an intermediate position, contacts bridged by said roller when said arm is in said intermediate position, an electro-

magnet connected to be energized by the bridging of said contacts, an armature movable by said magnet, means connecting said pivotal member to said armature so as to tend to pivot said member to withdraw said projection from said path of travel when said magnet is energized, and means for delaying the pivoting of said member.

7. In an electric switching device, a snap-action switch including switch structure movable over a track between two terminal positions, a spring compressible to move said structure, a handle shiftable for compressing said spring, a member normally positioned in the path of travel of said structure for arresting movement thereof from either terminal position in an intermediate position with said spring still compressed, means actuated by the stopping of said structure in said intermediate position for withdrawing said member from said path of travel, whereby said spring may resume movement of said structure, and means for delaying withdrawal of said member for an appreciable period.

8. In an electric switching device, a snap-action switch including switch structure movable over a track between two terminal positions, a spring compressible to move said structure, a handle shiftable for compressing said spring, a member normally positioned in the path of travel of said structure for arresting movement thereof in an intermediate position with said spring still compressed, contacts bridged by said structure when the latter is in said intermediate position, an electro-magnet connected to be energized by the bridging of said contacts, an armature movable by said magnet, means connecting said armature to said member so as to tend to withdraw the member from said path of travel, whereby said spring may resume movement of said structure, and means for delaying withdrawal of said member for an appreciable period.

9. In an electric switching device, a snap-action switch including switch structure movable in either direction over a track between two terminal positions, a spring compressible to move said structure, a handle shiftable for compressing said spring, a pair of members pivoted adjacent to opposite ends of said track, a projection carried by each of said members and normally positioned in the path of travel of said structure for arresting movement thereof in an intermediate position with said spring still compressed, said structure contacting one of said projections when trav-

eling in one direction and contacting the other projection when traveling in the other direction, means actuated by the stopping of said structure in said intermediate position for pivoting said members to withdraw both of said projections from said path of travel, said pivoted members and projections being so arranged that the force of said spring opposes the pivoting of said members by said means when said structure contacts either of said projections, and means for delaying the withdrawal of said projections for an appreciable period.

10. In a switch having two extreme positions and an intermediate position, means capable of being conditioned to throw said switch from either extreme position to the other extreme position, a member movable to condition said means, means for interrupting the throw of the switch from either extreme position to the other and for retaining the switch for an appreciable period in the intermediate position, contact means arranged to be bridged only when said switch is in one of said extreme positions, contact means arranged to be bridged only when said switch is in said intermediate position, and contact means arranged to be bridged both when said switch is in said one of said extreme positions and in said intermediate position.

11. In an electric switching device, a snap-action switch including switch structure movable over a track between two terminal positions, means for moving said structure, a member normally positioned in the path of travel of said structure for arresting movement thereof from either terminal position in an intermediate position, contact means arranged to be bridged only when said structure is in one of said extreme positions, contact means arranged to be bridged only when said structure is in said intermediate position, contact means arranged to be bridged both when said switch is in said one of said extreme positions and in said intermediate position, an electro-magnet connected to be energized when said second mentioned contact means are bridged, said electro-magnet including an armature, means connecting said armature to said member so as to tend to withdraw said member from said path of travel when the electro-magnet is energized, and means for delaying the withdrawal of said member.

FERMAN C. DOUGHMAN.
ERIC C. WAHLBERG.
